PORTABLE POWER-DRIVEN FILE

Frank A. Cole, Pittsburgh, Pa.

Application December 3, 1946, Serial No. 713,691

5 Claims. (Cl. 29—76)

1

This invention relates to a metal-surfacing apparatus in the nature of a file or smoother and, in particular, to a portable device having a driving motor associated therewith.

It is frequently desirable in the metal-working arts to smooth the surface of a member after it has been worked on. Hand filing is commonly resorted to for this purpose but it is a slow and costly operation and is characterized by lack of uniformity because of the human factor. I have invented a portable power-driven tool capable of smoothing metal surfaces uniformly and rapidly, which is practically as simple to operate as an ordinary file but is capable of performing a surfacing operation much more efficiently and satisfactorily. In a preferred embodiment of the invention, an open-bottomed housing is provided with a horizontal cross wall above the bottom thereof sloping downwardly at each end forming guideways. A yoke is slidable along each guideway. A plurality of toothed blades extend between the yokes, each blade being secured to one yoke and slidable on the other, the toothed edges of the blades being exposed at the open bottom of the housing. A shaft is journaled in the housing and is adapted to be driven by a motor mounted thereon. Barrel cams on the shaft cause reciprocation of the yokes and blades on rotation of the shaft. Lifter plates extend along the blades and are mounted for vertical movement relative to the housing whereby to lift the apparatus on the retraction stroke of the blades. Disc cams on the shaft cause reciprocation of the lifter plates in timed relation to the reciprocation of the toothed blades.

A complete understanding of the invention may be obtained from the following detailed description and explanation referring to the accompanying drawings for the purpose of illustration. In the drawings,

Figure 1 is a vertical longitudinal section through the apparatus showing parts in elevation;

Figure 2 is a bottom plan view with parts broken away and parts omitted for the sake of clearness; and

Figures 3 and 4 are transverse sections on the planes of lines III—III and IV—IV, respectively, of Figure 1 looking in opposite directions.

Referring in detail to the drawings, an open-bottomed housing 10 rectangular in plan has side walls 11, end walls 12 and top 13. A cross wall 14 extending between the ends and sides is located intermediate the bottom and top of the housing and is secured therein in any convenient

2

manner as by welding. The end portions of the wall are plane and slope downwardly forming guideways 15. Yokes 16 and 17 are slidable along the under surface of the guideways.

5 A plurality of toothed blades 18 extend between the yokes 16 and 17. Alternate blades are secured to one yoke and slidable on the other. Each blade has holes at one end for bolts 19 inserted through the spaced depending sides of 10 yoke 17 and a slot at the other end for sliding on similar bolts on the yoke 16, or vice versa. The teeth on alternate blades are oppositely directed so that a cutting stroke is effected when the blades are pulled toward the ends of the housing 15 10.

20 A shaft 20 is journaled longitudinally of the housing 10 in bearings 21 in the ends of the housing and bearings 22 on the wall 14. The shaft is driven by a motor 23 which may conveniently be mounted on the top 13 of the housing. A worm 24 on the motor shaft meshes with a wormwheel 25 on the shaft 20 between the bearings 22. Frusto-conical barrel cams 26 are secured to the shaft 20 for reciprocating the 25 yokes 16 and 17. Each cam has a circumferential slot 27 adapted to accommodate the ball head of an actuator 28 extending upwardly from one of the yokes through a slot 29 in the sloping end portion or guideway of the wall 14. It will be 30 apparent that, by reason of the slope of the guideways, the blades will be forced downwardly as they are moved toward the ends of the housing. The tool, being bodily manipulated by hand, is free to rise, of course, as the blades advance but the reaction of the weight of the tool urges the blades against the work. To facilitate manipulating the tool, the motor 23 may conveniently be mounted in a bracket 30 having a hand grip 31 provided with a trigger switch 32 for 35 controlling the motor.

40 In order to raise the tool and the toothed edges of the blades 18 from the surface being worked on as the blades are retracted, i. e., pushed toward the center of the housing, I provide a plurality of lifter plates 33 extending alongside the toothed blades and between adjacent blades. The plates 33 are secured at their upper edges to a horizontal plate 34. The lower edges of the plates 33 are adapted to bear on the surface of 45 the work. Guide pins 35 extend upwardly from the plate 34 through bearings 36 in the wall 14. The pins 35 are urged against disc cams 37 on the shaft 20 by compression springs 38 surrounding the bearings for the guide pins and engaging 50 the flanges 39 thereon. The springs 38 urge the 55 flanges 39 thereon.

plates 33 and 34 upwardly at all times. The cams 37 are so shaped and positioned on the shaft 20 as to move the plates 33 and 34 downwardly while the yokes 16 and 17 are being moved inwardly to retract the blades to a position for starting a cutting stroke. When the blades have reached this position, the cam permits the springs 38 to raise the plates 33 and 34, thereby lowering the housing so that the toothed edges of the blades engage the work. It will thus be apparent that the housing 10 vibrates vertically during the operation of the device.

Certain of the blades 18, specifically those designated 18a, extend beyond the ends of the other blades and outwardly through a slot 40 in one end of the housing. The projecting portions of these blades may be used in the manner of a saw for rough cutting or ripping operations.

It will be apparent that the invention provides a portable power-driven machine for smoothing metal surfaces which is characterized by numerous advantages. In the first place, the apparatus is relatively simple and inexpensive to manufacture. Its use, furthermore, does not require any special skill. The action of the cutting blades is quick and accurate. All moving parts are enclosed except the toothed edges of the blades. Since alternate blades are reciprocated in opposite directions and thus have their teeth facing in opposite directions, the device as a whole is non-creeping. The dust and chips resulting from the smoothing operation are fed out freely because the cutting blades are lifted clear of the work on the retraction stroke. On the cutting stroke, the weight of the tool, as explained above, serves to apply the necessary working pressure to the blades.

Although I have illustrated and described only a preferred embodiment of the invention, it will be recognized that changes in the construction disclosed may be made without departing from the spirit of the invention or the scope of the appended claims. Instead of using individual cutting blades assembled in two cooperating groups, the individual blades of which are interleaved, the blades of each group may be formed by slotting a block, the block being secured to one of the yokes. Instead of mounting the driving motor on the housing, furthermore, I may drive the shaft 20 through a flexible shaft from a motor mounted elsewhere. Ordinarily, however, the construction illustrated is to be preferred since the weight of the motor helps to hold the toothed edges of the blades against the work.

I claim:

1. In a portable power-driven file for smoothing metal surfaces or the like, in combination, a plurality of toothed blades in parallel arrangement adapted to form a substantially planar toothed filing surface, each of said blades having all of its teeth directed in the same direction and alternate ones of said blades having their respective teeth directed in opposite directions, all of said blades having their respective teeth directed in one direction comprising one group and all of the remaining of said blades comprising another group, a yoke attached to each of said groups of said blades having their teeth respectively directed in the same direction, means for moving said yokes apart substantially parallel to the length of said blades to effect a simultaneous linear cutting stroke in opposite directions, whereby said portable power-driven file is substantially non-creeping during operation.

2. In a portable power-driven file for smoothing metal surfaces or the like, in combination, a plurality of toothed blades in parallel arrangement adapted to form a substantially planar toothed filing surface, alternate ones of said blades having their teeth oppositely and respectively directed axially thereof, a yoke attached to each group of said blades having their teeth directed in the same direction, means for moving said yokes apart substantially parallel to said toothed surface and to the longitudinal axes of said blades to effect a simultaneous cutting stroke in opposite directions, said means for moving being further adapted to move said yokes toward each other to effect a simultaneous linear retraction stroke of said blades, an independent lifting surface for said yokes, and means for extending said lifting surface while said yokes are being so moved toward each other, whereby all of said blades are maintained in relatively sharp condition by being kept out of contact with said metal surfaces or the like during said retraction stroke.

3. In a portable power-driven file for smoothing metal surfaces and the like, in combination, a plurality of toothed blades set on edge in parallel arrangement and adapted to form a substantially planar toothed filing surface, adjoining blades of said plurality having their teeth oppositely directed along the longitudinal axes of said respective blades, a yoke attached to each group of said blades having their teeth directed in the same direction, each said yoke having sliding engagement with the group of said blades having their teeth directed in the opposite direction, said sliding engagement being spaced from the place of attachment between said last-mentioned group and its respective yoke, means for simultaneously moving said yokes apart at the same rate substantially parallel to said toothed surface and to said longitudinal axes of said blades to effect a simultaneous linear cutting stroke in opposite directions against said metal surfaces or the like, and means for simultaneously moving said yokes toward each other at the same rate substantially parallel to said toothed surface and to said longitudinal axes of said blades to effect a simultaneous linear retraction stroke of said blades, whereby simultaneous respective cutting and retraction movement of all blades occurs in linear opposed equal force fashion to prevent creeping forces during operation, each of said blades being supportably engaged by said yokes at spaced points along the length thereof.

5. 4. In a portable power-driven file for smoothing metal surfaces or the like, in combination, a plurality of toothed blades set on edge in parallel arrangement and adapted to form a substantially planar toothed filing surface, adjoining blades of said plurality having their teeth oppositely directed along the longitudinal axes of said respective blades, a yoke attached to each group of said blades having their teeth directed in the same direction, each said yoke having sliding engagement with the group of said blades having their teeth directed in the opposite direction, means for simultaneously moving said yokes apart at the same rate substantially parallel to said toothed surface and to said longitudinal axes of said blades to effect a simultaneous linear cutting stroke in opposite directions against said metal surfaces or the like, means for simultaneously moving said yokes toward each other at the same rate substantially parallel to said toothed surface and to said longitudinal axes

of said blades to effect a simultaneous linear retraction stroke of said blades, lifting plates positioned on edge between said blades and adapted to be reciprocated vertically, means for moving said lifting plates against said metal surfaces or the like during said linear retraction stroke of said blades to lift said blades off of said metal surfaces or the like during retraction, whereby said portable power-driven file is substantially non-creeping during operation and said yokes maintain said blades in planar relation to said metal surfaces or the like.

5. In a portable power-driven file for smoothing metal surfaces or the like, in combination, a plurality of toothed blades set on edge in parallel arrangement and adapted to form a substantially planar toothed filing surface, adjoining blades of said plurality having their teeth oppositely directed along the longitudinal axes of said respective blades, a yoke attached to each group of said blades having their teeth directed in the same direction, each said yoke having slotted engagement with the group of said blades having their teeth directed in the opposite direction, said slotted engagement being spaced from the point of attachment between said group and its respective yoke, cams for simultaneously moving said yokes apart at the same rate substantially parallel to said toothed surface and to said longitudinal axes of said blades to effect a simultaneous linear cutting stroke in opposite directions against said metal surfaces or the like, downwardly and outwardly sloping guideways for said yokes adapted to move said blades toward said metal surfaces or the like during said cutting stroke, said cams being further adapted to simul-

taneously move said yokes toward each other at the same rate substantially parallel to said toothed surface and to said longitudinal axes of said blades to effect a simultaneous linear retraction stroke of said blades in opposite directions, lifting plates positioned on edge between said blades and adapted to be reciprocated vertically, cam means for moving said lifting plates against said metal surfaces and the like during said linear retraction stroke of said blades to lift said blades away from said metal surfaces and the like during retraction, whereby said portable power-driven file is substantially non-creeping during operation and said blades are maintained in relatively sharp condition by being lifted during said retraction stroke.
